DUAL TERMINAL CONNECTOR LUG

Ignazio Leonardo, Mountainside, N.J., assignor to The Thomas & Betts Co., Incorporated, Elizabeth, N.J., a corporation of New Jersey

Filed Dec. 19, 1962, Ser. No. 72,902

Term of patent 14 years

(Cl. D26—1)

FIG. 1 is a perspective view of a dual terminal connector lug showing my new design as seen from its front end;

FIG. 2 is a similar perspective view of the dual terminal connector lug as seen from its opposite end;

FIG. 3 is a top plan view of the same;

FIG. 4 is an end view in elevation of the same; and FIG. 5 is a side elevational view of the connector lug design shown in the preceding figures.

I claim:

The ornamental design for a dual terminal connector lug, as shown.
